DESIGN FOR A DRESS

Marion Haon, New York, N. Y.

Application July 29, 1939, Serial No. 86,320

Term of patent 3½ years

To all whom it may concern:

Be it known that I, Marion Haon, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific dress disclosed of the specific tucking on the waist and upper portion of the skirt as shown.

I claim:

The ornamental design for a dress, substantially as shown and described.

MARION HAON,
